(57) CLAIM

The ornamental design for a carafe, as shown and described.

DESCRIPTION

FIG. 1 is a front perspective view of a carafe showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the bottom surface region of the carafe represents unclaimed subject matter and forms no part of the claimed design. The unshaded central circular region in FIGS. 1 and 6 forms no part of the claimed design.
